Edward G. Oldfield.

UNITED STATES PATENT OFFICE.

EDWARD G. OLDFIELD, OF BORDENTOWN, NEW JERSEY.

MACHINE FOR MAKING BRICK, TILE, &c.

Specification of Letters Patent No. 31,126, dated January 15, 1861.

To all whom it may concern:

Be it known that I, EDWARD G. OLDFIELD, of Bordentown, in the county of Burlington and State of New Jersey, have invented, 5 made, and applied to use a certain new and useful Improvement in Machines for Making Brick, Tiles, &c.; and I do hereby declare that the following is a full, clear, and exact description of the nature of my said 10 invention, reference being had to the accompanying drawing, making part of this specification, wherein—

Figure 1, is a plan of my improved press, and Fig. 2, is a vertical section at the line 15 *x, x.*

Similar marks of reference denote the same parts.

The nature of the said invention consists in a series of propeller blades acting to 20 force the clay through a contracting duct whereby the mass is consolidated and passed out through a die of the shape to be given the tile, brick, or other article, and while passing out of said die the clay is lubricated 25 by the application of water or any coloring liquid. By this means I am enabled to use clay of the usual consistence as dug from the ground without mixing the same with water although I am not limited in this particular 30 but can use clay of more or less plasticity.

In the drawing *a*, is a frame of any suitable character carrying the parts.

b, is the main shaft, geared by the wheels *c*, and *d*, to the counter shaft *e*, that is provided with the stirrers *f* inside the hopper *g*, by means of which the clay supplied to the said hopper *g* is mixed and caused to pass to the machine.

h, is a drum on the end of the shaft *b*, 40 which drum coincides with the lower end of the hopper *g*, at one side, and with the lower side of the die *s*, and between this die *s*, and hopper *g* is the duct *m*. The cylinder *h*, is provided with slots receiving the 45 pistons or propellers *i*, *i*, that are connected by the links *k*, *k*, to the fixed stud *l*, which is eccentric to the shaft *b*, so that as the drum *h*, is revolved by the shaft *b*, and carries the propellers *i*, *i*, around with it.

50 These propellers are projected and retracted by the stud *l*, as represented and in their movement they take the clay in the hopper *g* and force the same through the duct *m*, which consolidates the clay as carried 55 through said duct in consequence of the tapering form and the clay thoroughly con-

solidated and compacted passes through the throat *r*, into the die *s*, which die is to be of the size and shape of the brick tile or other article to be produced, and the continuous length issuing from the die *s*, is to be cut off into the required lengths by means of a vibrating wire or other suitable device.

To prevent rupture to the duct *m*, in consequence of any stone or unusual pressure I make use of the safety plate *n*, kept down by the strut *o*, lever *p* and weight *q*, and to insure the accurate and uniform movement of the clay in passing through the die *s*, 70 I make use of the air vessel *t*, in which the pressure makes the clay rise and the confined air causes the delivery of clay from the die to be as uniform as possible.

u, *u*, are rollers acting above and below 75 the clay in the die *s*, to slightly compress the same and cause it to move freely, and these rollers are driven by gearing and a belt *w*. *v*, is a watertight casing surrounding the rollers *u* and die *s*, and when water 80 is introduced into this casing it lubricates the surface of the clay rendering it much smoother. And if desired metallic oxides or other coloring matter may be applied to the surface of the clay by these rollers *u*, *u*. 85

The operation of this press as a whole will be apparent from the foregoing, and it will be seen that I am enabled to work my clay much stiffer than heretofore usual, hence there will be less shrinkage, and the 90 articles produced will be much more uniform and perfect.

What I claim and desire to secure by Letters Patent is—

1. The propellers *i*, *i*, traveling in the 95 tapering duct *m*, in the manner specified to compress and consolidate the clay as set forth.

2. The safety plate *n*, applied to the duct *m*, in the manner and for the purposes specified.

3. The arrangement of the air vessel *t*, rollers *u*, *u*, and casing *v*, in combination with the die *s*, in the manner and for the 100 purposes specified.

In witness whereof I have hereunto set my signature this twelfth day of December 1860.

EDWARD G. OLDFIELD.
